UNITED STATES PATENT OFFICE

WILLIAM F. EPPENSTEINER, OF RAHWAY, NEW JERSEY, ASSIGNOR TO THE AMERICAN METAL COMPANY (LIMITED), OF NEW YORK, N. Y., A CORPORATION OF NEW YORK

CAR LOADER

Application filed October 16, 1930. Serial No. 489,121.

This invention relates to apparatus for loading granular or pulverulent material into box cars or for performing other similar functions.

5 In loading such material into box cars, it has to be passed through one of the side doors and carried to the opposite ends of the car body. It is important to minimize the requirement of manual labor for shoveling or 10 trimming the material within the car, especially with materials which give off an unwholesome or even poisonous dust, where the labor is highly detrimental to the health of the operatives. An example of such material is zinc oxide, for which the specific apparatus hereinafter described has been especially designed and is well suited.

The car loader provided by the present invention includes a conveyor of any suitable 20 type adapted to convey the material in substantially horizontal direction and movable to enable it to be introduced through the side door of a freight car; a mounting for such conveyor, including a swiveled support 25 around which the conveyor may swing in a horizontal plane, and a carriage or bogie supported on casters or rollers on a preferably level platform, so that it may participate in any such swinging movement and may move 30 longitudinally of the conveyor when the latter is being introduced into or withdrawn from the car through the side door; a means for driving the conveyor is conveniently located on said carriage.

35 The preferred embodiment is illustrated in the accompanying drawings, wherein—

Figure 1 is a plan of the apparatus, the conveyor being partly broken away in mid-section and various positions being shown in 40 dotted lines;

Fig. 2 is a side elevation, partly in vertical longitudinal section through the conveyor, illustrating it in operation within a car body;

45 Fig. 3 is a vertical transverse section on the line 3—3 in Fig. 2; and

Fig. 4 is an inverted plan, partially in section, on the line 4—4 in Fig. 3.

In the drawings A indicates the car body 50 and B a side door or door opening thereof.

C is the conveyor as a whole, D being its frame or casing, and E its conveying means which, in this case, is shown as a screw, although other types of conveying means may be substituted. The material to be loaded is introduced into the conveyor from above through a chute F which connects, by a detachable portion G, with a receiving opening H in the top of the conveyor casing. The material is carried through the conveyor and discharged from an opening or spout I at or near its outer end.

The conveyor is supported on a support J, which is swiveled at K so that it may be turned sidewise to swing the conveyor around in a horizontal or approximately horizontal plane. To fasten it in any desired position, the base or platform L, on which the support is mounted, is provided with an arc groove a engaged by a clamping bolt b on the supporting structure or by any other suitable anchoring means. At the end or what may be referred to as the inner end of the conveyor is located a carrier M which may consist, as shown, of a small platform on which is mounted the driving mechanism for operating the conveyor. This carrier M is mounted on rollers c, which may be casters and which roll freely on the top of the platform L. The means for operating the conveyor may consist of an electric motor or other suitable engine d, the shaft e of which enters a gear casing f in which is any suitable type of reducing gearing whereby a drive is imparted to the shaft g of the conveyor. This mechanism will, of course, be provided with some suitable controlling means (not shown).

Any suitable engaging connection may be applied between the under side of the conveyor frame A and the swiveled support J. The construction shown includes a grooved roller h turning in bearings on the swiveled support and on the top of which rides a rail i which is fastened beneath the frame D. This rail i serves to strengthen the frame D and also serves as its means of support on the saddle which is constituted by the roller h (and which, except for anti-friction purposes, might be any sliding type of saddle). The construction is such that the conveyor

may be moved endwise, this rail *i* rolling on the roller *h*. The support *J* has side flanges or guides *k*, which serve for stiffening, and also has an additional guide for the sides of the conveyor frame. For a screw conveyor, this frame is in the form of a trough, as usual,—this being shown in Fig. 3.

In operation the car to be loaded is brought alongside the platform *L*, at which time the conveyor is pulled back so that its outer end stands approximately in the position indicated by the dotted lines *x* in Fig. 1 and its carriage *M* is in the position shown by the dotted lines *M'* in that figure, and the carriage *M* is then pushed forward to project the conveyor into the side of the car; this movement may carry the carriage to the position indicated at *M*² and the end of the conveyor to the position shown at *x'*; then,—or, if preferred, simultaneously with the forward movement,—the conveyor is swung around to an oblique position such that its spout *I* is carried as far as is desired into the car toward one end thereof. This may bring the parts to the position shown in full lines in Fig. 1 or to a position of greater obliquity within the limits of the arc-shaped slot *a*. The extreme position is not shown in Fig. 1 because the scale does not permit the entire length of the car to be shown; it is desirable to carry the conveyor in toward the end of the car far enough to stack the material so far in that no shoveling, or only the minimum of shoveling afterward for trimming the load, may be necessary. When as much material has been introduced with the conveyor in this position as is desired, it is then drawn back and swung around to the opposite angle to a position which may be indicated, for example, by the dotted lines *x*² in Fig. 1, or in practice to a farther position. In each position of angular adjustment the screw *b* should be tightened in order to hold the conveyor against swaying or being displaced laterally.

It will be understood that the details of construction may be varied within the limits of the skill of a constructor or as required according to the engineering conditions involved.

It will also be understood that the volume of material directed down through the chute *F* will be controlled in any of the known ways,—as by slides, an example of a slide being shown at *N* in Fig. 2. Before pulling back the conveyor, the flexible connecting section *G* may be disconnected after closing the slide *N*; or, by mounting the chute high enough and making the connection *G* of sufficient length, this may be a flexible chute or conduit, which will accommodate itself to any movement of the conveyor.

I claim as my invention:

1. A car loader comprising a supporting platform alongside which the car may be

placed, a conveyor, a swivelled support for the conveyor mounted on said platform exterior to the car, the conveyor movable longitudinally on said support, and a carriage supported on the platform and having wheels for universal movement thereon, said carriage rigidly attached to the inner end of the conveyor to participate in the endwise and swinging movements thereof.

2. A loader according to claim 1, with driving means for operating the conveyor carried on said carriage.

In witness whereof, I have hereunto signed my name.
